UNITED STATES PATENT OFFICE.

ROBERT E. OTTMAN, OF EAST ORANGE, NEW JERSEY, ASSIGNOR TO WESTERN ELECTRIC COMPANY, INCORPORATED, OF NEW YORK, N. Y., A CORPORATION OF NEW YORK.

PROTECTIVE DEVICE.

1,406,681.

Specification of Letters Patent. Patented Feb. 14, 1922.

Application filed October 29, 1920. Serial No. 420,464.

To all whom it may concern:

Be it known that I, ROBERT E. OTTMAN, a citizen of the United States, residing at East Orange, in the county of Essex and ⁵ State of New Jersey, have invented certain new and useful Improvements in Protective Devices, of which the following is a full, clear, concise, and exact description.

This invention relates to protective devices, and more particularly, to an improved method of assembling protector blocks used in open space cut-outs.

A type of protector block to which this invention is applicable, consists of a block ¹⁵ of non-conductive material such as porcelain in which is secured a conducting electrode of carbon or similar conducting material. The block of conducting material is depressed a few thousandths of an inch ²⁰ below the surface of the non-conducting block in order that the assembled unit may be placed in opposition to a second block of conducting material and provide an open space air gap between adjacent conducting ²⁵ surfaces, without resorting to the use of a non-conducting separator.

It is an object of the present invention to provide an improved method for assembling a conducting electrode in a block of ³⁰ non-conducting material and depressing the surface of the electrode accurately a predetermined distance below the surface of the non-conducting block.

It is a further object of the invention to ³⁵ provide a method of manufacture which will permit assembling protector blocks accurately and at a low cost.

To attain these objects and in accordance with a feature of the invention, a method ⁴⁰ of manufacture is provided in which the conducting electrode is first placed in its approximate position and secured by some cementing material such as a low melting point glass. It is next heated to a tempera- ⁴⁵ ture at which the cement becomes plastic or softened and the assembled block is then placed in a jig provided with a die member which permits the electrode member being accurately depressed the distance required ⁵⁰ to give the specified separation required for the assembled cut-out. This and other features of the invention will be more clearly understood by reference to the attached drawing in which Fig. 1 shows a protector block in which an electrode is roughly se- ⁵⁵ cured in place; Fig. 2 is a longitudinal view of the block of Fig. 1 after the surfaces have been ground flush; Fig. 3 discloses a number of protector blocks being carried by a belt conveyor through an electrical fur- ⁶⁰ nace; Fig. 4 discloses a jig in which the heated blocks are placed and the electrodes accurately positioned; and Fig. 5 shows a completely assembled block lying adjacent to a plain carbon block to provide a com- ⁶⁵ plete cut-out as used in service.

Referring now to these drawings, Fig. 1 is a cross-section view showing a block 7 of porcelain or similar insulating material in which is secured a carbon electrode 8, ⁷⁰ this electrode being held in place by means of a cement 9 consisting preferably of a low melting point glass as disclosed in a Patent No. 1,324,334 of December 9, 1919, to H. Boving. No attempt is made to place ⁷⁵ the electrode 8 accurately in position and the surfaces of the carbon block are not ground.

In Fig. 2 there is shown a longitudinal section view of the block shown in Fig. 1, after the surface has been ground so that the ⁸⁰ surface of the electrode 8 is in the same plane as the surface of the block 7. The blocks are next heated so that the cementing material 9 becomes plastic. This is prefer- ⁸⁵ ably done as shown in Fig. 3 by placing the blocks on a moving belt 11 which passes through an electric furnace 10, the speed of the belt and the heat of the furnace being such as to insure the material 9 being plastic when the blocks emerge from the other side ⁹⁰ of the furnace. The block is next placed in a jig as shown in Fig. 4, this jig being pro- ⁹⁵ vided with a die member 12 having a projecting portion 13, which is adapted to align with the electrode 8. By applying pressure to the handle or lever 14, a block 14 oper- ¹⁰⁰ ates to press the block 7 against die 12, thus accurately depressing the carbon electrode 8 a distance equal to the height of the pro- ¹⁰⁵ jection 13. Since the die member 12 is of hardened steel very carefully machined, it is possible to accurately depress the electrode the required distance without resorting to undue care on the part of the operator.

In Fig. 5 there is disclosed a completed block in which the carbon electrode is de- ¹⁰⁵ pressed the required distance. This block is

shown lying adjacent to a rectangular carbon block 15 to form a complete protector unit as used in service.

Although it is preferable to grind the surfaces of the electrode and of the non-conducting block after the electrode is secured within the non-conducting block it is, of course, possible to surface the portions separately and then obtain the advantages of this invention in finally locating the electrode accurately in position.

What is claimed is:

1. A method of assembling a protector block which consists in cementing a conducting electrode in a non-conducting block, heating the block until the cementing material becomes softened, accurately depressing the electrode a predetermined distance and allowing the cementing material to cool.
2. A method of assembling a protector block which consists in cementing a conducting electrode in a block of non-con-

ducting material, grinding the surface of said block and electrode until the surfaces lie in the same plane, heating the block 25 until the cementing material becomes plastic, depressing the electrode and allowing the cementing material to harden.

3. A method of assembling a protector block which consists in securing a conducting electrode in a block of non-conducting material by means of a low melting point glass, grinding the surfaces of said block and electrode until the surfaces lie in the same plane, heating the assembled block until 35 the low melting point glass becomes plastic, placing the heated block in a jig, applying pressure to depress the electrode the desired distance and allowing the low melting point glass to harden. 40

In witness whereof, I hereunto subscribe my name this 22nd day of October A. D. 1920.

ROBERT E. OTTMAN.
